UNITED STATES PATENT OFFICE

107,312

DESIGN FOR A STRIP SHINGLE OR THE LIKE

Albert C. Fischer, Chicago, Ill.

Application April 19, 1937, Serial No. 68,862

Term of patent 14 years

To all whom it may concern:

Be it known that I, Albert C. Fischer, a citizen of the United States, residing at Chicago, in the county of Cook and State of Illinois, have invented a new, original, and ornamental Design for a Strip Shingle or the like, of which the following is a specification, reference being had to the accompanying drawing, forming part thereof, in which:

Figure 1 is a perspective view of a strip shingle embodying this invention.

Figure 2 is a plan view of the same.

Figure 3 is a side elevation of the same, and

Figure 4 is a front elevation of the same.

The dominant feature of the invention is the combination of an undulating upper surface and an overhanging formation at the butt end, which combination is somewhat suggestive of snow drifts. The full lines show the design which may be repeated in the dotted line portions which have been broken away.

I claim:

The ornamental design for a strip shingle or the like substantially as shown and described.

ALBERT C. FISCHER.
